UNITED STATES PATENT OFFICE.

GEORGE OUELLETTE AND NAPOLEON LAJOIE, OF LEWISTON, MAINE, ASSIGNEES OF
ONE-THIRD TO CHARLES M. STONE, OF LEWISTON, MAINE.

STOP-MOTION ACTUATOR.

Application filed December 18, 1922. Serial No. 607,693.

To all whom it may concern:

Be it known that we, GEORGE OUELLETTE and NAPOLEON LAJOIE, citizens of the United States, residing at Lewiston, in the county of Androscoggin and State of Maine, have invented certain new and useful Improvements in Stop-Motion Actuators; and we do declare the following to be a full, clear, and exact description of the invention, such as will enable others skilled in the art to which it appertains to make and use the same.

Our invention relates to improvements in automatic stop motions for looms and relates more particularly to an attachment designed primarily for the Crompton-Knowles automatic box loom, for the purpose of bringing the usual stop motion into play in case a shuttle should become lodged in the shuttle box.

When changing bobbins on an automatic loom, it frequently happens that the bobbin does not take the correct position in the shuttle, with the result that this shuttle is trapped partly in and partly out of the shuttle box. This leaves the binder open and renders the protection rod inoperative and thus the loom continues to run and the other shuttle coming from the opposite end of the loom will strike the trapped shuttle and break out the warp, also frequently breaking the filling battery or other parts of the loom. It is the object of our invention however to provide an extremely simple and inexpensive, yet a highly efficient and reliable attachment whereby a trapped shuttle will act upon a movable stop motion operating device mounted on the breast beam for the purpose of engaging it with a part of the stop motion mechanism, bringing the loom to an immediate standstill, novel provision being made for automatically disengaging said stop motion operating device from the stop motion part operated thereby, when the proper work has been performed, thereby preventing possible injury to parts which might otherwise occur on completion of the lay's movement toward the breast beam.

With the foregoing in view, the invention resides in the novel subject matter hereinabove described and claimed, the description being supplemented by the accompanying drawings.

Figure 1 is a plan view of the invention showing its relation with well known loom parts.

Figure 2 is a side elevation of the parts disclosed in Fig. 1.

Figure 3 is an enlarged elevation of the attachment separate from the loom.

Figure 4 is a top plan view partly in horizontal section.

Figure 5 is a vertical transverse sectional view as indicated by line 5—5 of Fig. 4.

Figures 6 and 7 are side elevations showing different positions of parts.

The invention has been illustrated in connection with a loom including the usual breast beam B, lay L, shuttle box SB, shuttle S, picker P, shipper lever SL, and stop motion lever SM for releasing said shipper lever. We mount our stop motion operating device upon one end of the breast beam and it is operated by movement of the lay toward this beam in case a shuttle becomes lodged from any cause, as indicated in Fig. 1, but means are provided for automatically disengaging said device from the stop motion lever SM, as soon as the latter is operated.

The numeral 1 designates a support having a horizontal base flange 2 and an upwardly extending vertical flange 3, the base 2 being adapted to be secured by bolts or the like to the breast beam B, for which purpose it is formed with slots 4. The flange 3 is located on a line running in the same direction as that in which the lay L moves and a movable carrier is mounted upon this flange, the carrier being here shown in the form of a horizontal slidably mounted bar 5 which contacts with the outer side of the flange 3 and is formed with longitudinal slots 6 receiving bolts or the like 7 which extend outwardly from this flange. Any suitable means are provided for moving the carrier 5 normally toward the lay L and for this purpose, we have shown an apertured lug 8 extending from said carrier and receiving a horizontal rod 9 in its aperture, said rod extending from an appropriate post 10 which projects laterally from the flange 3. A coiled spring 11 surrounds the rod 9 and acts against the lug 8, an appropriate adjustable collar 12 being provided on said rod, against which the spring reacts. One end of the carrier 5 is preferably offset as indicated at 13 and is provided with an appropriate shoe 14 adapted to be struck by a lodged shuttle as indicated in Fig. 1, when the lay moves toward the breast beam.

A stop motion operating member is car-

ried by the carrier 5 for engagement with the stop motion lever SM when said carrier is moved in the manner above set forth. This member is by preference in the form 5 of a horizontal arm 15 pivoted at 16 to the carrier 5 adjacent its offset end 13. The manner in which the arm 15 acts against the lever SM is disclosed in Fig. 6, but as soon as this lever has been actuated to release 10 the shipper lever SL, upon partial movement of the lay toward the breast beam, permitting the latter to move to an operative position, the arm is disengaged from the lever SM automatically, as seen in Fig. 15 7, as the lay completes its movement. This prevents possible injury from resulting to any parts of the loom or attachment, which would occur if the device were permitted to establish a rigid connection between the lay 20 and the lever SM, before the lay had completed its movement toward the breast beam. For the purpose of effecting the automatic release of the arm 15, we have shown a cam 17 adjustably secured by a suitable bolt and 25 slot connection 18 to the base flange 2 of the support 1. This cam is co-operable with an inclined shoulder 19 at one end of a recess 20 which is cut in the lower edge of the arm 15 to normally receive said cam as 30 shown in Fig. 6. By comparing Figs. 6 and 7, the manner in which the arm 15 is automatically released from the cam 17 will be clearly understood.

In order that the arm 15 may operate in 35 the desired manner, it is advisable that the pivot 16 thereof shall be rather loose. Movement of said arms away from the flange 3 however is prevented by a suitable guide finger 21 which may well be held in place 40 by the bolt of the connection 18.

By employing the construction shown or 45 a substantial equivalent thereof, an attachment is provided which is simple and inexpensive, may be easily attached to a loom, and will be very effective for bringing the machine to a standstill in case the shuttle 50 should become lodged from any cause, thereby effectively preventing "break-outs" with their consequent trouble and loss of time.

Excellent results have been obtained from 55 a device constructed in accordance with the present disclosure and we therefore consider this construction as preferable. It is to be understood however that within the scope of the invention as claimed, numerous minor changes may be made.

We claim:

1. In a loom attachment having a stop motion operating device adapted to be 60 moved by a lodged shuttle on the loom lay, said operating device having a portion adapted to contact with and operate a stop motion control upon partial movement of the lay toward the usual breast beam; means for automatically moving said por-

tion of said operating device positively out of contact with the stop motion control as the lay completes its movement toward the breast beam.

2. In a loom attachment having a movable carrier adapted to be moved by a lodged shuttle on the loom lay, and an operating member movably mounted on said carrier and adapted to contact with and operate a stop motion control upon partial movement 75 of the lay toward the usual breast beam; means for automatically moving said operating member positively out of contact with the stop motion control as the lay completes its movement toward the breast beam. 80

3. A device of the class described comprising a support adapted to be mounted on the breast beam of a loom, a slidable carrier mounted on said support for movement in the same direction as the lay of the loom 85 and adapted to be operated by a lodged shuttle when the shuttle-carrying lay moves a portion of the distance toward the breast beam, a stop motion operating member permanently connected in an operative manner to and slidably bodily with said carrier for acting on a part of a stop motion when said carrier is operated by partial movement of the lay toward the breast beam, and means for automatically and positively moving said stop motion operating member out of operative contact with the aforementioned stop motion part while the lay completes its movement toward the breast beam. 95

4. A device of the class described comprising a support adapted to be mounted on the breast beam of a loom, a slidable carrier mounted on said support for movement in the same direction as the lay of the loom and adapted to be operated by a lodged shuttle 100 when the shuttle-carrying lay moves a portion of the distance toward the breast beam, a stop motion operating member pivoted to said carrier for acting on a part of a stop motion when said carrier is operated by partial movement of the lay toward the breast beam, and means for automatically swinging said stop motion operating member on its pivot and disengaging it from the aforementioned stop motion part while the lay 110 completes its movement toward the breast beam. 115

5. A device of the class described comprising a support adapted to be mounted on the breast beam of a loom, a carrier on said support for movement in the same direction as the lay of the loom and adapted to be operated by a lodged shuttle when the shuttle-carrying lay moves a portion of the distance toward the breast beam, a stop motion operating member movably and permanently connected in an operative manner to and movable bodily with said carrier for acting on a part of a stop motion when said carrier is operated by partial movement of the lay 120 125 130

- toward the breast beam, and co-acting means on said support and said stop motion operating member for automatically moving the latter out of operative contact with the 5 aforementioned stop motion part while the lay completes its movement toward the breast beam.
6. A device of the class described comprising a support having a horizontal base portion for attachment to the breast beam of a loom and a vertical flange rising from said base portion, a slide parallel with and mounted for movement on said vertical flange in the same direction as the lay of 10 the loom, said slide being adapted to operate by a lodged shuttle upon partial movement of the shuttle carrying lay toward the breast beam of the loom, an arm over said base portion pivoted to said slide and adapted 15 to operate a part of a stop motion, and a cam carried by said base portion for automatically releasing said arm from the aforementioned stop motion part while the lay completes its movement toward the breast 20 beam, said arm having a surface co-operable 25 with said cam.
7. The combination with a loom having a breast beam, a lay movable toward and from said breast beam, and a stop motion control; of an operating device for said control mounted movably on said breast beam, said operating device having a portion normally disposed for contact with said control, and another portion in the path of a lodged 30 shuttle on the lay to move said operating device and said control as the lay moves part of the distance toward the breast beam, and means for automatically moving said first-named portion of said operating device positively out of contact with said control as 35 the lay completes its movement toward the breast beam.
8. The combination with a loom having a breast beam, a lay movable toward and from said breast beam, and a stop motion control; of a movable carrier mounted on said breast beam, an operating member for said control movably mounted on and movable bodily with said carrier, said operating member being adapted to contact with said stop motion control, said carrier being adapted to be struck by a lodged shuttle on said lay as the latter moves part of the distance toward the breast beam, whereby to 45 move said carrier and operating member and actuate said control, and means for automatically moving said operating mem- 50 ber positively out of contact with said control as the lay completes its movement toward the breast beam. 60
9. A device of the class described comprising a carrier adapted to be movably mounted upon a loom frame and to be operated by a lodged shuttle, and an operating member for a stop motion part, said member being movably mounted on said carrier and being adapted to co-act with means for releasing it from the stop motion part. 65
10. A device of the class described comprising a carrying bar adapted to be slidably mounted upon a loom frame and to be operated by a lodged shuttle, and an operating arm for a stop motion part pivoted to said carrying bar, said arm being adapted for co-action with means for releasing it 70 from the stop motion part. 75
11. A device of the class described comprising a carrying member formed from a bar and having a straight portion adapted to contact with a supporting member, said straight portion being slotted to receive means for attaching it slidably to the supporting member, said carrier having an offset end to be struck by a lodged shuttle and having means to engage a spring device. 80 85
12. A device of the class described comprising an operating arm for a stop motion part, a carrier to which said arm is pivoted, said carrier having a cam for engagement with stationary means to release said arm 90 from the stop motion part.
13. A device of the class described comprising a supporting member having a base and a flange rising therefrom, said flange being adapted to slidably support a shuttle-operated member, and a cam carried by the base portion of said supporting member adjacent said flange. 95
14. A device of the class described comprising a supporting member having a base portion and a flange rising therefrom, a cam plate resting on said base portion adjacent said flange, an upstanding guide finger near said flange having a base resting on said cam plate, and a fastener passing through said base of said finger, said base portion of said supporting member, and said cam plate, provision being made for permitting adjustment of said cam plate parallel with said flange. 100 105 110
- In testimony whereof we have hereunto affixed our signatures.
